STABILIZING PLATFORM

Frederick D. W. Searing, Newark, N. J.

Application February 24, 1938, Serial No. 192,275

3 Claims. (Cl. 114—191)

This invention relates to improvements in and combinations with devices for stabilizing ships' furniture and has special reference to improvements in platforms so mounted and counterpoised that by reason of the universal motion of the mounting members, persons or articles resting upon the platform do not partake of the rolling and pitching motions of the ship.

One of the objects of the invention is to combine with said stabilizing device a chair and a bed.

Another object of the invention is to provide improvements in a stabilizing device for use on shipboard and made up of a base frame adapted to rest upon or be supported by some portion of a ship, a pair of track supporting members each supporting on its upper edge a concavely curved track, hinges for pivotally uniting the track members to the frames whereby they may be raised into an upstanding, operative position or knocked down for transportation or storage, an intermediate frame having two pairs of wheels for running on the tracks of the base frame, a pair of track supporting members supporting on their upper edges concavely curved tracks, hinges uniting these track members to the intermediate frame whereby they may be pivotally raised into an upstanding, operative position transversely of the lines of the tracking of the wheels carried by such frame, the track members also being adapted to fold down and an upper frame having two pairs of wheels for running on the tracks of the intermediate frame, and to combine said stabilizing device with a folding chair, also to combine said stabilizing device with a set of springs with head and foot attachments to form a bed.

Another object of the invention is to provide four species of tracks for the track members and combining them with appropriate wheels to run upon said tracks so as to avoid friction and so that the wheels may be properly retained on the track without unnecessary friction against the retaining members or sides of said tracks, and to provide means for fastening the track to the supporting track member and to provide four species of tracks with appropriate wheels for so doing in an economical manner.

Another object of the invention is to provide a folding footrest for chair which when unfolded may be supported by folding braces attached to projections from the under side of the seat of the chair, and which may be locked in position when unfolded and ready for use.

Another object of the invention is to provide

a top platform for the stabilizing device, which in combination with supports rising from the front wheel shanks of the intermediate platform will receive and hold the chair parts in a firm and proper position having regard to the proper disposition of the weight of the occupant of the chair.

Another object of the invention is to provide a mode of placing the wheels supporting the platform so as to reduce the tendency of the chair or bed to oscillate from body movements of the occupant of the chair, and also in the case of the chair to so place the wheels as to keep the front wheels from projecting through the bottom of the chair.

Another object of the invention is to provide a mode of attaching dress protectors to the chair to prevent clothing from contacting the tracks, and in the case of the bed to prevent bed clothing or other articles from contacting the tracks.

Another object of the invention is to provide a mode of combining a set of bed springs with head and foot parts attached for resting on the bed stabilizer, and means of fastening said set of springs with head and foot attachments in proper position to the top platform of the stabilizer by downward movement so that it is held in a firm position against motion in all directions except upward motion used in removing the springs from the stabilizer, having regard to the proper balance when occupant is using the bed.

Another object of the invention is to provide a mode of attaching adjustable hoods to certain wheels on the bed stabilizer to prevent the bed springs from touching the wheels.

Another object of the invention is to provide a mode of arranging certain of the wheels close together so that the tracks on the front and foot of the bed need not come above the height of the mattress, and thus make the bed easy of access.

Another object of the invention is to provide a mode of attaching the weight control to fixed and folding levers attached to the bottom of the top platform so as to give the weight control a leverage pull in causing adjustment to boat motion and in resisting oscillation from body movements from occupant of chair or bed.

Another object of the invention is to provide a mode of bracing and locking the track supporting members in a rigid, true alignment when unfolded so as to properly accommodate the wheels without friction against the sides of the tracks or the retaining track members and so

that the bracing members will not interfere with the folding of the tracks.

Another object of the invention is to provide a mode of constructing wheel shanks pivoted to the wheels but rigidly fastened to platforms, and also to provide wheel shanks for the front of chair to furnish support to the chair and to retain same in a fixed position, said supports being preferably T-shaped, running transversely across and under the front of the chair seat.

In the drawings accompanying this specification, one practicable embodiment of my invention is illustrated, in which drawings:

Figure 1 is a view looking at this device from the side with a chair mounted on the stabilizer.

Fig. 2 is a plan view of the stabilizer for the chair looking at the device from the top.

Fig. 3 is a cross-sectional view of the chair mounted on the stabilizer.

Fig. 4 is a cross-sectional view of the chair stabilizer taken at about the plane of the line 7—7 in Fig. 2.

Fig. 5 is a side view of the locking device of the footrest support.

Fig. 6 is a view of the underside of the chair and footrest.

Fig. 7 is a view looking at this device from the front side with a set of bed springs with head and foot attachments mounted on the stabilizer, the showing being on a reduced scale.

Fig. 8 is a cross-sectional view taken at about the plane of the line 2—2 in Fig. 7 of the bed springs with head and foot attachments mounted on the stabilizer.

Fig. 9 is a plan view of the bed stabilizer looking at the device from the top.

Fig. 10 is a view of the underside of the table attachment.

Fig. 11 is a cross section through the middle cleat attached to the underside of the table attachment taken on line 11—11 of Fig. 10.

Fig. 12 is a view of the underside of the desk attachment.

Fig. 13 is a cross section through the middle cleat attached to the underside of the desk attachment taken on line 13—13 of Fig. 12.

Fig. 14 is a front view of a wheel having openings in the rim to accommodate riser or track flange.

Fig. 15 shows the end view of a set of tracks, one having a flange running transversely along the middle and one flat track without a flange.

Fig. 16 is an end view of a set of tracks, one with a high flange on which the wheel runs without touching the base of the track, and one flat track without flange.

Fig. 17 is the end view of a set of tracks with upward slanting flange sides, to accommodate and retain wheels.

The form of the device illustrated herein comprises three super-imposed members or frames, the lowest of which is particularly designed for resting upon the flooring of the deck of a ship, although it may be otherwise supported, and the upper platform in the chair stabilizer is represented by a pair of longitudinally disposed planks or members 12 and 13, in Fig. 2, and a pair of transverse members 14 and 15, in Fig. 2, and is the chair supporting member of the device, the openings 16 and 17 calculated to receive the side members of the back of the chair, and the supports 19 and 20 extending upward from the front wheel shanks operating in conjunction with the back wheel shanks 21, in Fig. 1, retain and hold the chair in a firm position as to move-

ments forward and back, and the openings 16 and 17, in Fig. 2, hold the chair in a firm position as to side movement so that by unfolding the chair and by dropping same by a downward movement, the chair is firmly locked to the top platform in proper position against motion in any direction except upward, in removing the chair from the stabilizer.

One purpose of my invention is to mount this top frame supporting the necessary elements of a chair and footrest on two sets of wheels running on transversely disposed tracks to afford a universal adjustment so that the top platform of the chair which it supports will remain level despite the rolling and pitching of the ship in any direction. For purposes of greater stability and rapid resistance to boat motion and to avoid top-heaviness, and for the purpose of overcoming inertia of the parts and of friction of the rollers and their associated parts, and for the purpose of resisting oscillation due to body movements of the occupant of the chair, I attach to the top platform by means of two folding levers, 22 and 23, Fig. 1, pivoted to two right angle pieces 24 and 25, Fig. 3, and to two non-folding side levers 26 and 27, Figs. 1 and 3, somewhat shorter than the folding levers, a counterpoise 161, Fig. 3, preferably in the nature of a heavy body whose weight is approximately 30 to 40 lbs., and is determined by the approximate weight of the person or body which is to be supported by the stabilizer. The purpose of using levers for fastening the weight control to the top platform is to increase the effectiveness of the weight control by giving it a greater leverage pull in maintaining the top platform in a level position at all times against body motion and body movements of the occupant of the chair, and to give quick adjustment to boat motion.

Four species of tracks preferably of non-rust metal may be used, each and all of which will cause the wheels to run upon the tracks so as to avoid friction and so that the wheels will be retained on the track, and which may be provided economically.

First is the preferred form whereby a wheel, Fig. 14, having a round opening in the rim sufficient to accommodate a flange traversing the center of a track, Fig. 15, so that said flange will have considerable play room in the rim opening on each side of the rim opening which covers flange and which serves to retain the wheel upon the track, the other track being of flat metal without the middle flange, Fig. 15, and the wheel on said flat metal track having no opening in its rim, the two wheels having the opening in the rim covering the flange track acting as guide wheels and providing means for retaining the wheels on the tracks, thus avoiding friction and jamming of the wheels in case the track members should get out of true alignment.

A second species of tracks and wheels consists of having both tracks with a middle flange and both wheels to accommodate the flange on each track with more play room between the sides of the flange and the sides of the opening in the rim so that both tracks and both sets of wheels aid in retaining the wheels on the track.

A third species of wheels and tracks is, as in Fig. 16, wherein one set of wheels have openings in the rim and the opposite set runs on a flat track, but the flange is of such height with respect to the opening in the rim of the wheel that the wheel runs on the flange and not on the

track, the opposite set of wheels running on a flat track.

The fourth species of tracks and wheels are shown in Fig. 17, consisting of flat track—preferably of metal—the width of the track-supporting member and having upwardly sloping sides, the two sloping sides being considerably wider apart than the width of the wheels to run on it so as to allow considerable play room for the wheels between the sides of the tracks, the said tracks being curved to fit the track-supporting members and being fastened thereto by means of screws running through the bottom of the track or through flanges extending from the bottom of the track.

The chair to be mounted on the stabilizer consists of a back 28, seat 33, footrest 30, and arms 37, Fig. 1. The back of the chair is pivoted 32, Fig. 3, to the side member of the seat 33 so that the seat folds upward. The arms of the chair are pivoted 34 so that they also fold upward with the seat. The arms each consist of two members, namely, the upright 35, which is pivoted to the seat of the chair at 36, and the top of the upright which is pivoted to the front of the arms 37 by means of hinges, the footrest 30 being attached to the front of the chair seat by means of hinges 38, Fig. 3 so that the footrest folds down and under the seat, and is supported when unfolded and in position for use by two supports, preferably of metal, 39, pivoted to strips 40 fastened to the bottom of the chair and extending downward a suitable distance to give the supports 39 a proper resistance to sustain the footrest 30. The other ends of the supporting braces 39 engage the footrest 30 at a screw with a round head 41, Fig. 1, which moves in an opening 45 traversing the length of the braces 39 up to the point of extreme end of the opening 45, which opening is curved to receive and retain the screw when the footrest is extended for use. The screw is locked in this opening by means of a flat strip, preferably of metal 42, pivoted to the end of the brace at 43, Fig. 5, having a small handle 44 so that the strip 42 holds the screw in its position when the screw is in the opening to accommodate it, and the screw may be released by turning the strip 42 on its pivot and the braces 39 permit the chair to be folded when unlocked, by means of the screw 41 traversing the opening 45 along the length of the brace.

To the side members of the back of the chair are fastened metal braces 46, Fig. 3, which by contacting the underside of the seat members, limit the backward movement of the chair to a proper position, and said braces 46 on each side of the chair fit into the openings 16 and 17, Fig. 2, in the top platform on each side thereof and limit the movement of the chair from side to side, and together with the TT shaped metal supports 19 and 20, Fig. 2, in front of and under the chair, and the wheel shanks 21, Fig. 1, lock the chair in a true and proper position for use when same is unfolded and placed upon the top platform by a downward movement. Underneath the chair, and attached to the lower part of the arm of the chair member 35, is a metal cross-bar 50, Fig. 1, to give the arms proper rigidity. The front part of the bottom of the chair is supported by two TT-shaped crosspieces 19 and 20 rising from and attached to the wheel shanks of the front wheels, which TT-shaped supports are the right height to give the bottom of the chair a proper slant downward from the front of the chair to the back so that the chair is held in

a fixed accurate position, and the weight of the person is properly balanced on the stabilizer. Dress or clothing guards 51 are attached to the under part of each side of the front of the chair immediately over the front track and have the same curve as the track. These guards are for the purpose of keeping the clothing of the occupant of the chair from contacting the tracks. The method of supporting the folding sides of the chair stabilizer when unfolded and set for receiving the platforms is accomplished in the same manner as described in the stabilizing device for the bed both as to the track supports attached to the base frame and the track supports attached to the intermediate frame, as set forth on page 4 herein; similar parts in the drawings are designated by similar numbers with the addition of the letter *a* to each of such numbers.

The wheels 159 and 160, Fig. 2, are set close together to lessen the tendency to oscillation from body movement of the occupant of the chair, and also so that the track support 114a, Fig. 1, may be shortened so that it does not rise to an inconvenient height in order to accommodate the two close wheels 159, 160, Fig. 2, and also for the purpose of lowering the wheels 159, 160, so that they do not project through the bottom of the chair. The wheels 161 and 162 are set far enough apart to cause adjustment to boat motion. The wheels 163 and 164 are also placed closer together than those on the opposite track, 165 and 166, so as to lessen the tendency to oscillation from body movements of the occupant of the chair and also so that the track support of wheels 163 and 164 may be shortened, and access to the chair made more easy.

The bed consists of a set of springs 52, Fig. 7, with end brackets at head and foot of springs 53. Said brackets are without legs and engage the springs 52 by means of projections from spring 54 in bracket openings 55 and are fastened to said springs by bolt 56. The side members of the springs 52 rest upon raised members 57 fastened to the top platform 58 and braced by braces 59, Fig. 9. In the top of said supports 57 and 58, Fig. 7, are openings 107 and 108 for receiving projections, preferably metal bolts fastened to the bottom of the springs, one at 61 and one on opposite side of springs for the purpose of fastening the bed springs to their support in a proper position, having regard to the weight of a person occupying the said bed and the distribution of their weight at a proper balance. To give additional bracing to the bed springs and to facilitate placing them in proper position, side braces 102 and 103 are attached to the supporting member 57 and similar braces 104 and 105 are attached to the opposite supporting member 57, so that when the bed springs are placed upon the stabilizer, the bolt at 61 and also a similar bolt on the opposite member of the bed springs fit into openings 107 and 108, Fig. 9, and hold the bed in proper position as to weight distribution and prevent movement toward the head or foot of the bed, and the four projecting members 102, 103, 104 and 105 hold the springs in firm position so that they cannot be moved sideways, the bed being thus held in proper place and against movement in any direction except upward, the motion used in taking the springs off the stabilizer. The wheels 62, 63, Fig. 7, of the intermediate frame on the front or lower track supporting member 64 are

set closer together than the wheels 65 and 66 running on the back track supporting member, the wheels 65 and 66 being sufficiently far apart to cause adjustment to boat motion.

5 The wheels 62 and 63 are set close together to lessen the tendency to oscillation from body movements of the occupant of the bed and also so that the track support 64, Fig. 7, may be shortened so that it does not rise above the mattress on the springs 52. The wheels 67 and 68, Fig. 8, supporting the top platform at the foot of the bed are also placed close together to avoid oscillation and also to shorten the track 71, Fig. 8, so that it also will not rise above the 10 mattress and will be of approximately the same height as the contiguous track support 64, thus making easy access to the bed. The back wheels 69 and 70 of the top platform are set wide enough apart to cause adjustment to boat motion and 15 also contain adjustable hoods 73 and 74, Fig. 9, in order to prevent the springs under the weight of the occupant from touching the wheels. The brakes for the bed consist of movable strips, preferably of metal 74 and 75, Fig. 9. The said 20 25 metal strips contain oblong openings 76 and 77 and are held to the frame 58, Fig. 9, by means of round-headed screws 79, through said openings so as to permit the brake to be moved in and out of an opening to receive the end of said brake 30 in the adjacent track support. These brakes when set, fasten the top platform to the track supports of the top platform, and the intermediate platform has brakes 80 and 81 fastened to the track supports of the intermediate platform by round-headed screws and strips of metal similar to brakes 74 and 75 on the top platform. By moving the brakes 80 and 81, Fig. 9, the same can be moved into the opening in the track support connected with the base platform so that 35 40 by the operation of the full set of brakes, motion in all directions is stopped and the bed can be used as an ordinary bed at the convenience of the occupant. Small handles 82, 83, 84 and 85a are attached to the brakes to facilitate their 45 movement. In place of the metal strips described, ordinary bolts can be used when fastened in the place of the metal strips.

The weight control 168 for the bed is supported by four levers, 85, 86, 87 and 88, the one 50 opposite and parallel to 86, all of said levers being of the same length and fastened to the underside of the crosspieces 89 and 90, and extending downward at right angles to the crosspieces 89 and 90. The ends of the levers have 55 holes 91 containing a hook, and to this hook in each one of the ends of the levers are attached straps, preferably of canvas, by means of snap-buckles on the end of the strap, and the other end of the strap is attached to an eyelet in the 60 head of the weight by a snapbuckle attached to the other end of the said strap, the top of the weight control containing a depression so that the eyelets set therein do not project above the top rim of the depression, thus permitting the 65 various weights to be piled one on top of the other when the various beds are taken down and folded up. The said levers greatly increase the effectiveness of the weight by giving it a leverage pull from the ends of the levers and make 70 it quicker and more effective in overcoming friction and inertia and in holding the top platform level against boat motion and body movement of the occupant of the chair or bed. Bed clothing guards 158, preferably of metal are attached 75 to the underside of the bed springs covering the

tracks at the head of the bed on each side and at the foot thereof on each side. These guards have the same curve as the tracks they cover and are located about an inch above the track.

The method of supporting the folding sides 5 when unfolded and set for receiving the platforms is accomplished by having the bottom members of the bottom frame 92 and 93 of Fig. 7 project beyond the track support 64, and attached to track support 64 are two blocks or 10 cleats 94 and 95, fastened to the track support 64 so that the edges of the cleats 94 and 95 project slightly beyond the bottom of the track support 64 and when the track support is raised the cleats 94 and 95 contact the projecting members 92 and 93 and hold the track support under ordinary pressure so that it inclines slightly inward. The track is then forced to an upright perpendicular position by braces 96 and 97, Fig. 8, operating from the inside of the track support, which braces operate on pivots 98 and 99 and engage the track supports at projecting round-head screws, 100 and 101 fastened to the track supports. 15 20 25

Similar braces and cleats are at the opposite end of each track support so that all four corners of the bottom frame have braces similar to the two described. Thus the track supports are held in a firm and rigid position and are kept in true alignment, and wobbling under the weight 30 of the occupant and from the motion of the boat is prevented. This rigidity is further increased in the chair stabilizer by wooden braces 109, 110 and 111, Fig. 2, which are curved wooden or 35 metal braces fastened to the sides of the track supporting members, 114a and 156, Fig. 2, set into projecting screws 112 and 113, and locked to said screws by hooks pivoted to the said brace 109, and the hook part engaging an eyelet 157, Fig. 1, to prevent the brace from being knocked out 40 of position, and similar means are used to fasten braces 110 and 111, Fig. 2. The bracing of the intermediate track supports 114 and 158, Fig. 7, is obtained by placing the track supports on the supporting frame so that the supporting frame projects at 116 and 117, Fig. 7, and by fastening to each of the folding track supports blocks 118 and 119, said blocks projecting beyond the bottom of the track support so that block 118 contacts the projecting frame 116 and block 119 50 contacts projecting frame 117 so as to hold the track supports under ordinary pressure in a slightly inward inclined position. Similar blocks are fastened to the other ends of each of the track supports and contact in like fashion the projecting platform. The track supporting members are then forced to, and held in a perpendicular position by braces 120 and 121, Fig. 9, from the inside of said track supporting members pivoted to the bottom member of the intermediate platform at 122 and 123, and similar braces at other 55 end of each track support, engage the track supporting members at the projecting screw heads 124 and 125, Fig. 9, and similar screw heads at other end of each track support. Thus without 60 interference with the movement of the platforms, the upstanding track supports are held firmly and rigidly and in true alignment. 65 70 75

Brakes for the chair are provided for the purpose of holding the chair stationary when the 70 boat is not rolling or pitching, so that the chair may be used as an ordinary non-adjusting chair under such circumstances, at the will of the occupant. The brakes consist of three parts calculated to prevent motion on the curved tracks 75

in any direction. The brake for stopping motion on the curved tracks from one side to another of the person sitting in the chair consists of a single piece of metal 126, Fig. 3, pivoted on to the end of an upright piece of metal 127 set into the middle of a block 48, of either wood or metal, which block 48 is fastened to the bottom of the top platform at about the middle. The upright piece of material or metal 127, Fig. 3, has an oblong opening about $\frac{3}{4}$ inch long and about $\frac{1}{8}$ inch wide. When the upright piece of metal is placed in the middle of the block of wood, a wire nail or other piece of metal is driven through the wood and through the opening in the metal so that the upright piece of metal when used as a handle will cause the metal strip 126, Fig. 3, to which it is attached to go forward and back as desired and when the metal goes forward, it penetrates into the side of the back track support at 128 and prevents motion from side to side of a person sitting in the chair. The metal strip 126 which penetrates the track support and which is pivoted to the upright piece of metal 127, runs along the middle of the opening of the block of wood 48, abovementioned, in which the brake is set, and is retained in its position by metal pieces set across the opening in the bottom of the wooden block. The brakes for stopping motion on the other two tracks consist of two metal pieces 129 and 130, Fig. 4. The said strips, preferably of metal, 129 and 130, contain oblong openings through which round-headed screws fasten the strips to the back track supporting member which rests upon the intermediate frame. The said strips contain at the inner lower end metal projections about $\frac{1}{2}$ inch long 131 and 132 and about $\frac{1}{8}$ inch in diameter, which are pivoted to upright pieces of metal 133 and 134, which upright pieces of metal are in turn pivoted to the back track supporting member of the intermediate frame 135 by pivots 49, preferably round-headed screws driven through the oblong opening in or about the center of said upright strips 133 and 134, so that the upright pieces of metal 133 and 134 may be used as levers to force the metal strips into the sides of the upright track supports when the brakes are set, and to force them out when the brakes are off. These two brakes hold the intermediate platform from motion front and back and all three brakes when set hold the platforms locked against motion in any direction. Ordinary bolts

may be used in place of the brakes described when fastened in place of the metal strips.

Wheel shanks

The wheel shanks 138 and 139, Fig. 8, are pivoted to the wheels 67 and 68 respectively and are rigidly fastened underneath the frames at 140 and 141, and all the wheel shanks in both the chair stabilizer and the bed stabilizer are rigidly fastened to the platforms in like fashion 10 and not pivoted thereto. The wheel shanks are so placed that it seems to be unnecessary to fold them down, and more satisfactory adjustment is obtained by rigid attachment to the platforms, and the wheels can be set more easily in proper 15 position than if pivoted to the frames.

It is to be understood that the form of my invention herewith shown and described is to be taken as a perfect example of the same, and that various changes in the shape, size and arrangement of parts may be resorted to, without departing from the spirit of my invention or the scope of the subjoined claims.

Having thus described my invention, what I claim and desire to secure by Letters Patent is:

1. In a base for selfleveling ships' chairs which include superposed frames each formed to provide pairs of oppositely disposed arcuate tracks of equal radius on the upper surfaces thereof, one track of each pair formed by a smaller segment of arc than the other track of said pair, pairs of axle means rigidly mounted on the frames the axles of each pair being spaced apart, wheel means on the axles rotatably engaging said tracks, the wheels of each pair of wheels on each track of lesser segment being mounted closer together than the wheels on the other track of said pair whereby said pairs of wheels on the tracks of less segments are more insensitive to motion than are the wheels on the other tracks.

2. In a device as claimed in claim 1 wherein the track positioned at the front of the chair is formed by a less arc than the other track of said pair.

3. In a device as claimed in claim 1 wherein said tracks of lesser segments and the wheels thereon are formed to provide flanged interengaging surfaces and said tracks of greater segment and the wheels thereon are formed to provide flat interengaging surfaces.

FREDERICK D. W. SEARING.
